UNITED STATES PATENT OFFICE.

LOUIS A. ANDERSON, OF ATTLEBORO, MASSACHUSETTS, ASSIGNOR TO R & G COMPANY, INC., OF ATTLEBORO, MASSACHUSETTS, A CORPORATION OF MASSACHUSETTS.

BELT BUCKLE.

Application filed February 4, 1924. Serial No. 690,385.

To all whom it may concern:

Be it known that I, LOUIS A. ANDERSON, a citizen of the United States of America, and resident of Attleboro, in the county of 5 Bristol and State of Massachusetts, have invented new and useful Improvements in Belt Buckles, of which the following is a specification.

This invention relates to belt buckles of 10 that type in which the belt is retained in adjusted position by means of a clamping lever.

Principal objects of the invention are to provide a buckle adapted to be used with 15 belts of different thickness; simple in construction and having a minimum number of parts; and in which the pivots of the clamping lever are concealed and free movement of the lever is frictionally restrained.

20 In the accompanying drawings a preferred embodiment of the invention is illustrated by way of example.

Fig. 1 is a rear elevation of the buckle with its parts in clamping position, showing 25 one end of the belt in broken lines;

Fig. 2 is a bottom plan view of the buckle shown in Fig. 1;

Fig. 3 is an end elevation of the buckle viewed from the left hand side of Fig. 1;

30 Fig. 4 is a section on the line 4—4 of Fig. 1;

Fig. 5 is a section on the line 5—5 of Fig. 1, omitting the clamping lever;

Fig. 6 is an elevation of the clamping 35 lever; and

Fig. 7 is an edge view of the clamping lever;

The buckle herein disclosed consists of but two parts namely, a front plate and a 40 clamping lever.

The front plate 1 is preferably of sheet material, such for example as sterling silver, having its front face ornamented or plain as may be desired and of any suitable 45 size and shape. As illustrated the plate 1 is oval and its front face is slightly convex, its edges at its right and left ends being turned or rolled at 2 and 3 respectively to stiffen it as well as to enhance its appearance.

50 Rearwardly directed flanges 4 and 5 respectively extend integrally from the upper and lower edges of the front plate. Each of the flanges 4 and 5 has three tabs or ears integral with its rear edge. The outermost ears 6 and 7; 8 and 9 respectively of the up-

per and lower flanges extend inwardly substantially at right angles to their respective flanges and constitute guides or retainers for the end of the belt as the latter is moved into and out of engagement with the clamping lever. 60

The central ears 10 and 11 of the respective flanges are bent inwardly and forwardly so as to lie in spaced diverging relation to the inner surfaces of the flanges. These 65 central ears are somewhat resilient and constitute bearings for the clamping lever, being provided for this purpose with journal openings 12.

The clamping lever comprises an elongate 70 bar 13 provided at its opposite ends with projections 14 and 15 constituting pivot pins adapted to turn freely in the journal openings 12 of the respective bearing ears 10 and 11. The length of the bar 13 is such that 75 when the pivot pins are seated in the journal openings the ends of the bar bear frictionally against the resilient ears 10 and 11. The free movement of the lever is thus hindered so that undue swinging and rattling of the lever is prevented. 80

The bar 13 has a flange member 15^a projecting from its central part substantially perpendicular to the body of the bar. The flange proper is much shorter than the bar 85 but its free edge portion is extended in opposite directions towards the ends of the bar, forming arms 16 and 17 substantially parallel to the body of the bar but spaced therefrom. This extended free edge of the 90 flange is preferably thickened by bending it to form a rib or ledge 18 so that it may have a wide bearing upon the belt.

The bar 13 is also provided with an actuating arm 19 having a looped extremity 20 95 to which one end 21 of the belt is permanently secured.

The buckle thus consists of but two parts and when the pivot pins 14 and 15 of the lever are snapped into the bearing openings 100 in the ears 10 and 11, their ends are concealed within the spaces between the ears and the inner walls of the flanges 4 and 5. Thus the outer edges of the buckle are smooth and unbroken, presenting a much 105 neater appearance than is usual in buckles of this character.

One end 21 of the belt is firmly secured to the loop 20 and the opposite end is passed beneath the guide ears 7 and 9. The clamp- 110

ing lever is swung to inoperative position and the free end of the belt is passed beneath the latter and beneath the ears 6 and 8. When the belt is subjected to strain the 5 clamping lever assumes the position shown in Fig. 1 and the member 18 is brought into engagement with the belt. As the arms 16 and 17 of the flange 15^a are unsupported except at their inner ends they are somewhat 10 resilient and can accommodate themselves to belts of different thickness. Furthermore, the relatively short connection of the flange to the bar 13 renders it capable to a certain extent of flexure out of its normal 15 position when subjected to excess pressure. Another factor which contributes to the capability of the device to accommodate itself to belts of different thickness is the resiliency of the ears 10 and 11 and the side 20 flanges 4 and 5. With this arrangement excess pressure causes the side flanges to spring apart slightly so that the entire clamping lever may move bodily away from the inner surface of the front plate and breakage of 25 the clamping lever is substantially prevented even though the belt employed be of abnormal thickness.

I claim:

1. A two-piece belt buckle consisting of a 30 front plate having opposed rearwardly directed flanges, an ear extending inwardly and forwardly from the rear edge of each flange, said ears diverging from their respective flanges and each having a journal 35 opening, and a clamping lever having aligned pivot elements engaging the respective openings.
2. A belt buckle comprising a front plate provided at its upper and lower parts with 40 rearwardly directed flanges, an ear integral with each flange, said ears extending inwardly and forwardly in diverging relation to their respective flanges, each ear having a journal opening, and a clamping lever having 45 pivot members engaging the respective openings, the ends of said pivot members being disposed adjacent to the inner faces of the respective flanges.
3. A belt buckle comprising a front plate 50 having rearwardly directed flanges each provided with a resilient bearing member having a journal opening, said bearing members converging toward the rear face of the front plate, and a clamping lever having pivots 55 engaging the respective openings, the bearing members pressing resiliently against the lever adjacent to the pivots to retard its free movement.
4. A belt buckle having a unitary clamp-

ing lever comprising a belt receiving loop, a 60 belt clamping element and an elongate bar having pivot pins projecting from its ends, and a front plate having integral resilient bearing members provided with journal 65 openings for the pivot pins of the lever, said bearing members being so spaced relatively to the length of the bar as to cause them to press against the ends of the bar adjacent to the pivot pins to retard free swinging of 70 the lever.

5. A belt buckle comprising a front plate having a rearwardly directed flange, a pair of spaced guide ears projecting inwardly from the rear edge of each of the flanges, and a belt clamping lever pivoted to turn 75 about an axis substantially midway between the ears of said pairs.

6. A belt buckle comprising a front plate having rearwardly projecting flanges at its upper and lower edges, a pair of spaced inwardly directed guide ears projecting from the rear edge of each flange, a bearing ear also projecting from the rear edge of each flange intermediate the ears of the respective pairs, said bearing ears extending forwardly 80 and in diverging relation to the respective flanges and having journal openings, and a clamping lever having pivot pins disposed in the respective openings.

7. A belt buckle having a front plate and 90 a unitary clamping lever, the latter comprising a bar having pivot elements at its opposite ends and a belt engaging member, said member comprising a flange disposed centrally of the length of the bar and substantially perpendicular thereto, the flange being thickened at its free edge to provide a wide belt contacting surface, the end portions of the flange being spaced from the bar and 95 resilient.

8. A belt buckle having a front plate and 100 a unitary clamping lever, the front plate having rearwardly extending flanges provided respectively with divergent ears having bearing openings, and the lever comprising a bar provided with pivot pins at 105 its opposite ends engaging said bearing openings, said bar having a flange projecting substantially at right angles from its central part, the free edge of the flange being longer than the part united to the bar providing oppositely directed resilient arms spaced from the bar, the edge of said elongate portion of the flange constituting the 110 belt engaging portion of the lever.

Signed by me at Attleboro, Mass., this 115 28th day of January 1924.

LOUIS A. ANDERSON.
